(57) **CLAIM**

We claim the ornamental design for a putter face, as shown and described.

DESCRIPTION

FIG. 1 is a front elevational view of a putter face embodying our new design; and,

FIG. 2 is a sectional view of the putter face of FIG. 1, taken in the direction of the arrows 2—2 in FIG. 1, which reveals the depth of the spaces between adjacent circular projections in the putter face.
